UNITED STATES PATENT OFFICE

2,547,668

HEAT EXCHANGER

Clyde S. Simpelaar, Racine, Wis., assignor to
 Modine Manufacturing Company, Racine, Wis.,
 a corporation of Wisconsin

Application April 24, 1946, Serial No. 664,544

1 Claim. (Cl. 257—245)

1

This invention relates to heat exchangers of the type which employs gas, air as an example, for cooling a non-viscous fluid, such as water.

One of the objects of this invention is to provide a highly efficient heat exchanger of which the parts may be readily assembled and bonded together.

Another object is to provide a core for the heat exchanger composed of spaced rows of nested and bonded together channel shaped fin elements in which the rows are spaced apart by marginal spacing members, bonded to contiguous fin members and disposed at the sides of the core, whereby to provide fluid passages between the rows of fin members.

Another object is to provide partition members between the fin elements for causing the liquid to take a tortuous path through the passages in the core.

Other objects and advantages will appear in the course of this specification and with said objects and advantages in view this invention consists in the several novel features of construction, arrangement and combination of parts herein-after fully set forth and more particularly defined in the appended claim.

The invention is clearly illustrated in the drawing accompanying this specification, in which:

Fig. 1 is an end elevation of a heat exchanger with the upper part partly broken out, with the lower portion being a sectional view taken approximately on the line 1—1 of Fig. 2, and embodying a simple form of the present invention;

Fig. 2 is a horizontal section taken on the line 2—2 of Fig. 1;

Fig. 3 is a view partly in side elevation and partly in vertical, longitudinal section of the heat exchanger partly broken away; and

Fig. 4 is an enlarged vertical fragmental cross section taken on the line 4—4 of Fig. 2.

Referring to said drawing which is merely illustrative of one embodiment of the invention, the reference character 5 designates the core of the heat exchanger, 6 designates an inlet header and 7 an outlet header. An inlet pipe 8 opens to the inlet header 6 and an outlet pipe 9 opens from the outlet header 7.

The core 5 is composed of a plurality of spaced rows of nested and bonded together channel shaped fin elements 10. Between the rows of fin elements 10 are spacing members 11 disposed at the outer faces of the core. The fin elements 10 and spacing members 11 surround and enclose passageways 12 through which the liquid flows from the inlet header to the outlet header. The

2

spacing members 11 are bonded to the contiguous fin elements.

The fin elements are each composed of a cross wall 13 (see Fig. 4) from which extend side walls 14 which terminate in offset edge portions 15 and provide seats 15a for the next adjacent fin element to seat against.

The channels of all of the fin elements, except one endmost one, face in the same direction and are nested together as shown in Fig. 4. The endmost fin element 16 is of channel formation with its channel facing in the opposite direction. The fin element 16 is nested into the space between the offset edge portions of the next adjacent fin element, as clearly seen in Fig. 4.

Extending through the spaces between the adjacent fin elements are transversely extending spacing members 17, one extending from one spacing member 11 partway across the space and 20 the other spacing member 17 extending from the opposite spacing member 11 partway across the space. These spacing members 17 divide the passages 12 into tortuous passageways whereby the liquid will remain longer in the core than if it 25 were to flow in a straight path from the inlet to the outlet of the heat exchanger.

If desired, the inlet and outlet headers may be formed as parts of metal side walls 18 that extend from top to bottom of the core and may 30 be formed with flanges 19 overlying the outermost fin elements.

The reference character 20 designates bonding material by means of which the several parts of the heat exchanger are bonded together. In 35 constructing the heat exchanger embodying the present invention the fin elements are nested together in rows, the spacing members placed between the spaced rows of fin elements and the walls 18 placed upon the sides of the core. The 40 entire structure is then placed in a suitable furnace and heated to the fusing temperature.

In operation, the liquid to be cooled flows through the tortuous passageways 12 from the inlet header to the outlet header, and air flows 45 through the passageways formed by the channel shaped fin elements. The heat in the liquid is conducted from the liquid by the fin elements to the passageways therebetween and is carried away by the air flowing through said passageways.

Having thus described my invention, it is obvious that various immaterial modifications may be made in the same without departing from the spirit of my invention; hence, I do not wish to 55 be understood as limiting myself to the exact

form, construction, arrangement and combination of parts herein shown and described or uses mentioned.

What I claim as new and desire to secure by Letters Patent is:

In a heat exchanger, a plurality of spaced finned fluid passes, each comprising a series of channel-shaped fin elements having substantially parallel side walls, formed with offset edge portions, connected to an intermediate wall, said fin elements being interlocked with the offset edge portions of each element overlapping the side walls of the next adjacent element and bonded thereto to form an integral fluid pass, the heat transfer walls of which are composed of the respective side walls of the individual elements, each of said heat transfer walls lying substantially in a single plane extending substantially parallel to the plane of the other heat transfer wall, with said walls being connected by a plurality of longitudinally extending fins, marginal spacing members between and bonded to adjacent fluid passes at the sides of the core to form pas-

sages between adjacent finned passes, an inlet header communicating with said passages at one end of the structure, and an outlet header communicating with said passages at the other end of said structure, said headers being bonded to the structure.

CLYDE S. SIMPELAAR.
